UNITED STATES PATENT OFFICE.

DANIEL F. FERNEY, OF GRAND RAPIDS, MICHIGAN, ASSIGNOR TO GRAND RAPIDS SCHOOL EQUIPMENT CO., OF GRAND RAPIDS, MICHIGAN.

MITER-CLAMP.

1,226,763.

Specification of Letters Patent.

Patented May 22, 1917.

Application filed October 9, 1916. Serial No. 124,566.

To all whom it may concern:

Be it known that I, DANIEL F. FERNEY, a citizen of the United States, residing at Grand Rapids, county of Kent, State of Michigan, have invented certain new and useful Improvements in Miter-Clamps, of which the following is a specification.

This invention relates to improvements in miter clamps.

10 The main objects of this invention are: First, to provide an improved miter clamp in which all the clamping jaws are simultaneously adjusted to clamp the work.

Second, to provide an improved miter clamp having these features which may be adjusted to work of different dimensions.

Third, to provide an improved miter clamp in which all the clamping members are simultaneously adjusted and in which 20 the clamping stress is uniform on all of the clamping jaws.

Fourth, to provide an improved miter clamp which is capable of very rapid manipulation or adjustment to clamp or release the work and readily adjusted to work of different dimensions.

Fifth, to provide an improved miter clamp having these advantages which is comparatively simple, economical and durable in 30 structure.

Further objects, and objects relating to structural details, will definitely appear from the detailed description to follow.

I accomplish the objects of my invention 35 by the devices and means described in the following specification. The invention is clearly defined and pointed out in the claims.

A structure which is a preferred embodiment of my invention is clearly illustrated 40 in the accompanying drawing, forming a part of this specification, in which:

Figure I is a plan view of a structure embodying the features of my invention, the adjustment of the movable bed member being indicated by dotted lines.

Fig. II is a detail horizontal section on a line corresponding to the broken line 2—2 of Fig. IV, showing details of the adjusting and actuating mechanism.

50 Fig. III is a detail plan view, partially in horizontal section, the bed members being shown only by dotted lines in order to better show the operating mechanism.

Fig. IV is a detail vertical longitudinal section on a line corresponding to line 4—4 of Figs. I, II and III.

Fig. V is a detail section on a line corresponding to line 5—5 of Figs. I and II.

Fig. VI is a detail section on a line corresponding to line 6—6 of Fig. I, showing 60 the means for securing the rack preliminary to adjusting the bed members.

Fig. VII is a detail section on a line corresponding to line 7—7 of Figs. I and II, showing the means for locking the adjustable bed member in its adjusted position.

In the drawing similar reference characters refer to similar parts throughout the several views, and the sectional views are taken looking in the direction of the little 70 arrows at the ends of the section lines.

Referring to the drawing, the supporting frame in the structure illustrated comprises side members 1, and end members 2 and 3.

The bed or table members 4 and 5 are 75 mounted on the rails 6 fixed to the frame.

The bed or table member 4 of the structure illustrated is secured in a fixed position on the rails while the bed member 5 is adjustable thereon as indicated by dotted lines in 80 Fig. I.

To secure rigidity and facilitate adjustment the bed member 5 is provided with slides 7 having dovetailed recesses 8 in their under sides engaging dovetailed portions 9 85 on the rails (see Fig. VII).

Set screws 10 are provided for securing the bed member 5 in its adjusted positions. The means by which the adjustment of the bed member 5 is accomplished will be described later.

Each bed member is designed to carry a pair of clamping jaws 11 provided with slides 12 disposed in ways 13, the ways of each bed member being arranged at right 95 angles to each other to diverge outwardly. These ways are preferably in the form of grooves or channels 14 in the upper sides of the bed members and corresponding grooves or channels 14' in the under sides of the bed members (see Fig. V). In these channels 14' are pivot plates 15 connected to the jaw slides 12 by means of the bolts 16 disposed through the longitudinal slots 17. The bolts are provided with sleeves 18 to prevent the 105 clamping of the jaw slides when the bolts

are tightened. The pivot plates 15 are narrower than the way channels 14' (see Fig. II) so as to permit a limited oscillation thereof.

5 The jaws are actuated from the eccentrics 19 supported on the stub shafts 20 (see Fig. V).

I provide eccentric straps 21 coacting with the eccentrics 19 and threaded eccentric rods 22 having a swivel connection 23 within the straps. These rods 22 are threaded through the arms 24 on the plates 15. The eccentrics 19 are provided with pinions 25 arranged to mesh with the actuating members 26 and 27, 15 disposed between the pairs of pinions and provided with racks coacting therewith as clearly shown in Figs. II and III. In using the term pinions in the specification and claims I desire to be understood as contemplating segments.

The jaws having threaded connection with the rods 22 may be adjusted in their ways to accommodate work of different sizes by turning the rods which are provided with 25 cross pins 28 at their outer ends adapted to receive the clamp 29 (see Fig. II).

The actuating members 26 and 27 are connected by the rod 30 which is swiveled in the member 26 and has threaded connections 30 with the rack 27 (see Fig. IV).

The connecting rod 30 is provided with a hand wheel 31 at one end. The actuating members 26 and 27 are supported in ways 32 and 33, respectively, on the under side 35 of the bed members 4 and 5. The actuating members being connected by the rod 30 are simultaneously shifted longitudinally in their ways and, owing to their meshing with the pinions 25, simultaneously actuate the 40 eccentrics and, through the connections described, the clamping jaws. The actuating member 26 is provided with a rack 34 with which the segment 35 of the actuating lever 36 coacts, the actuating lever being mounted 45 at 37 at one end of the machine. The rod 30 is connected to the actuating member 27 through the nut 38 secured to the member and threaded upon the rod. When it is desired to adjust the bed member 5 the actuating 50 members are secured to the bed members 4 and 5 by means of the pins 39 disposed through holes 40 in the bed members and engaging holes 41 in the actuating members (see Fig. VI).

55 With the bed members and actuating members thus secured the turning of the rod 30 by means of the hand wheel 31 adjusts the bed member 5 on the rails 6 as may be desired, the bed member being, as stated, secured in its adjusted position by means of the set screws 10. This adjustment does not affect the clamping actuation of the jaws.

The jaws are, as stated, independently adjusted to accommodate different sizes of 60 work and to insure accuracy in adjustment

the bed members are provided with pairs of scales 42 for each clamp disposed one at each side of the ways 13 and provided with scale indicia for the arms of the angled clamping members.

The scale numerals have been omitted from the accompanying drawing as such scale indicia will be readily understood and applied.

With the parts arranged as I have illustrated and described I provide a machine which is capable of very rapid manipulation to clamp up or release the work and one in which the clamping stress on each of the clamp members is uniform and, so further, one which may be adjusted to work of varying sizes. The structure is simple and economical in its parts and very strong and durable.

I have not attempted to illustrate or describe various modifications which I contemplate as being desirable for certain adaptations of my invention as I believe the disclosure made will enable those skilled in the art to which my invention relates to embody or adapt the same as may be desired.

Having thus described my invention, what I claim as new and desire to secure by Letters Patent, is:

1. In a miter clamp, the combination of a frame provided with bed rails, a pair of bed members one of which is mounted on said rails for adjustment relative to the other, each bed member being provided with outwardly diverging jaw ways disposed at right angles to each other and comprising channels in the upper and under sides of said bed members, there being slots longitudinally of said channels, actuating members provided with double racks, ways for said actuating members disposed longitudinally of said bed members and centrally between their said jaw ways, a connecting rod for said actuating members having a swivel connection with one and a threaded connection with the other, means for detachably securing said actuating members to said bed members so that the adjustable bed member may be adjusted by the rotation of said connecting rod, means for securing said adjustable bed member in its adjusted positions on said rails, an actuating lever provided with a segment, one of said actuating members having a rack coacting with said segment, eccentrics disposed on said bed members at the sides of said actuating members and provided with eccentric straps and with pinions coacting with said double racks thereof, angled clamping jaws disposed in the upper channels of said jaw ways, pivot plates disposed in the under channels of said ways and connected to said jaws by pivots disposed through said slots, and eccentric rods having threaded connection with said plates and swivel con-

nection with eccentric straps so that the jaws may be adjusted by the rotation of said rods.

2. In a miter clamp, the combination of a pair of bed members one of which is adjustable relative to the other, each bed member being provided with outwardly diverging jaw ways disposed at right angles to each other and comprising channels in the upper and under sides of said bed members, there being slots longitudinally of said channels, actuating members provided with double racks, ways for said actuating members disposed longitudinally of said bed members and centrally between their said jaw ways, a connecting rod for said actuating members having a swivel connection with one and a threaded connection with the other, means for detachably securing said actuating members to said bed members so that the adjustable bed member may be adjusted by the rotation of said connecting rod, an actuating lever provided with a segment, one of said actuating members having a rack coacting with said segment, eccentrics provided with eccentric straps and with pinions coacting with said double racks, clamping jaws disposed in the under channels of said ways and connected to said jaws by pivots disposed through said slots, and eccentric rods having threaded connection with said plates and swivel connection with eccentric straps so that the jaws may be adjusted by the rotation of said rods.

3. In a miter clamp, the combination of a frame provided with bed rails, a pair of bed members one of which is mounted on said rails for adjustment relative to the other, each bed member being provided with outwardly diverging jaw ways disposed at right angles to each other and comprising channels in the upper and under sides of said bed members, there being slots longitudinally of said channels, actuating members provided with double racks, ways for said actuating members disposed longitudinally of said bed members and centrally between their said jaw ways, a connecting rod for said actuating members having a swivel connection with one and a threaded connection with the other, means for detachably securing said actuating members to said bed members so that the adjustable bed member may be adjusted by the rotation of said connecting rod, means for securing said adjustable bed member in its adjusted positions on said rails, eccentrics disposed on said bed members at the sides of said actuating members and provided with eccentric straps and with pinions coacting with said double racks thereof, angled clamping jaws disposed in the upper channels of said jaw ways, pivot plates disposed in the under channels of said ways and connected to said jaws by pivots disposed through said slots, and eccentric rods having threaded connec-

tion with said plates and swivel connection with eccentric straps so that the jaws may be adjusted by the rotation of said rods.

4. In a miter clamp, the combination of a pair of bed members one of which is adjustable relative to the other, each bed member being provided with outwardly diverging jaw ways disposed at right angles to each other and comprising channels in the upper and under sides of said bed members, there being slots longitudinally of said channels, actuating members provided with double racks, ways for said actuating members disposed longitudinally of said bed members and centrally between their said jaw ways, a connecting rod for said actuating members having a swivel connection with one and a threaded connection with the other, means for detachably securing said actuating members to said bed members so that the adjustable bed member may be adjusted by the rotation of said connecting rod, eccentrics provided with eccentric straps and with pinions coacting with said double racks, clamping jaws disposed in the upper channels of said jaw ways, pivot plates disposed in the under channels of said ways and connected to said jaws by pivots disposed through said slots, and eccentric rods having threaded connection with said plates and swivel connection with eccentric straps so that the jaws may be adjusted by the rotation of said rods.

5. In a miter clamp, the combination of a pair of bed members adjustable relative to each other, each bed member being provided with outwardly diverging jaw ways disposed at right angles to each other and comprising channels in the upper and under sides of said bed members, there being slots longitudinally of said channels, actuating members provided with double racks, means for simultaneously actuating said actuating members, eccentrics provided with eccentric straps and with pinions coacting with said adjusting member racks, clamping jaws disposed in the upper channels of said jaw ways, pivot plates disposed in the under channels of said ways and connected to said jaws by pivots disposed through said slots, and eccentric rods having threaded connection with said plates and swivel connection with eccentric straps so that the jaws may be adjusted by the rotation of said rods.

6. In a miter clamp, the combination of a pair of bed members provided with outwardly diverging jaw ways disposed at right angles to each other and comprising channels in the upper and under sides of said bed members, there being slots longitudinally of said channels, actuating members provided with double racks, means for simultaneously actuating said actuating members, eccentrics provided with eccentric straps and with pinions coacting with said

- adjusting member racks, clamping jaws disposed in the upper channels of said jaw ways, pivot plates disposed in the under channels of said ways and connected to said 5 jaws by pivots disposed through said slots, and eccentric rods having threaded connection with said plates and swivel connection with eccentric straps so that the jaws may be adjusted by the rotation of said rods.
- 10 7. In a miter clamp, the combination of a pair of bed members provided with outwardly diverging jaw ways disposed at right angles to each other and comprising channels in the upper and under sides of 15 said members, there being slots longitudinally of said channels, actuating racks, clamping jaws disposed in the upper channels of said jaw ways, eccentrics provided with eccentric straps and with pinions co- 20 acting with said racks, pivot plates disposed in the under channels of said jaw ways and connected to said jaws by pivots disposed through said slots, and eccentric rods having threaded connection with said plates, 25 and swivel connection with said eccentric straps so that the jaws may be adjusted on the rods by rotation of the rods.
8. In a miter clamp, the combination of 30 coacting clamping jaws, actuating racks, eccentrics provided with eccentric straps and with pinions meshing with said racks, an eccentric rod having swivel connection with said eccentric straps and threaded connection with said jaws whereby the jaws 35 may be adjusted on the rods by rotation of the rods, and scale indicia associated with said jaws.
9. In a miter clamp, the combination of 40 coacting clamping jaws, actuating racks, eccentrics provided with eccentric straps and with pinions meshing with said racks, an eccentric rod having swivel connection with said eccentric straps and threaded connection with said jaws whereby the jaws may 45 be adjusted on the rods by the rotation of the rods.
10. In a miter clamp, the combination of 50 bed rails, a pair of bed members one of which is mounted on said rails for adjustment relative to the other, each member being provided with jaw ways, actuating members mounted for longitudinal movement centrally between said jaw ways, a connecting rod for said actuating members having 55 a swivel connection to one and a threaded connection with the other, means for detachably securing said actuating members to said bed members so that the adjustable bed member may be adjusted by the rotation of 60 said connecting rod, means for securing said adjusting member in its adjusted positions, clamping jaws disposed in said ways, and operating connections for said actuating members to said jaws.
- 65 11. In a miter clamp, the combination of a pair of bed members one of which is adjustable relative to the other, each bed member being provided with jaw ways, actuating racks, a connecting rod for said actuating racks having a swivel connection with 70 one and a threaded connection with the other, means for detachably securing said actuating racks to said bed members so that the adjustable table bed member may be adjusted by the rotation of said connecting 75 rod, means for reciprocating said actuating racks, eccentrics provided with eccentric straps and with pinions coacting with said racks, clamping jaws disposed in said jaw ways, and eccentric rods having threaded 80 connection with said jaws and swivel connections with eccentric straps so that the jaws may be adjusted by the rotation of said rods.
12. In a miter clamp, the combination 85 of a pair of bed members one of which is adjustable relative to the other, each bed member being provided with jaw ways, actuating racks, a connecting rod for said actuating racks having a swivel connection 90 with one and a threaded connection with the other, means for detachably securing said actuating racks to said bed members so that the adjustable table bed member may be adjusted by the rotation of said connecting rod, clamping jaws disposed in said jaw ways, and operating connections for said 95 jaws to said racks.
13. In a miter clamp, the combination of 100 a pair of bed members one of which is adjustable relative to the other, each bed member being provided with jaw ways, actuating racks, a connecting rod for said actuating racks one of said racks being adjustable 105 on said rod, means for reciprocating said actuating racks, eccentrics provided with eccentric straps and with pinions coacting with said racks thereof, clamping jaws disposed in said jaw ways, and eccentric rods having threaded connection with said jaws 110 and swivel connections with eccentric straps so that the jaws may be adjusted by the rotation of said rods, said bed members having scale indicia associated with said jaws.
14. In a miter clamp, the combination of 115 a pair of bed members one of which is adjustable relative to the other, each bed member being provided with jaw ways, actuating racks, a connecting rod for said actuating racks one of said racks being adjustable 120 on said rod, means for reciprocating said actuating racks, clamping jaws disposed in said jaw ways, and operating connections for said rack to said jaws.
15. In a miter clamp, the combination of 125 a pair of bed members one of which is adjustable relative to the other, each bed member being provided with outwardly diverging jaw ways disposed at right angles to each other, actuating racks, means for si- 130

multaneously actuating said racks, means for adjusting and securing said adjustable bed member in its adjusted position, clamping jaws disposed in said ways, and eccentrics operatively connected to said jaws and racks, the connection for said jaws to said eccentrics being adjustable to permit the adjustment of the jaws to different work, said bed members having scale indicia associated with said jaws.

16. In a miter clamp, the combination of a pair of bed members one of which is adjustable relative to the other, each bed member being provided with outwardly diverging 15 jaw ways disposed at right angles to each other, actuating racks, means for simultaneously actuating said racks, means for adjusting and securing said adjustable bed member in its adjusted position, clamping 20 jaws disposed in said ways, and eccentrics operatively connected to said jaws and racks, the connection for said jaws to said eccentrics being adjustable to permit the adjustment of the jaws to different work.

25 17. In a miter clamp, the combination of diverging jaw ways, actuating racks, means for simultaneously actuating said racks, clamping jaws disposed in said ways, and

eccentrics operatively connected to said jaws and racks, the connection for said jaws to said eccentrics being adjustable to permit the adjustment of the jaws to different work, 30 said bed members having scale indicia associated with said jaws.

18. In a miter clamp, the combination of diverging jaw ways, actuating racks, means for simultaneously actuating said racks, clamping jaws disposed in said ways, and eccentrics operatively connected to said jaws and racks, the connection for said jaws to 35 said eccentrics being adjustable to permit the adjustment of the jaws to different work.

19. In a miter clamp, the combination of diverging jaw ways, actuating racks, means for simultaneously actuating said racks, clamping jaws disposed in said ways, and eccentrics operatively connected to said 40 jaws and racks.

In witness whereof, I have hereunto set 50 my hand and seal in the presence of two witnesses.

DANIEL F. FERNEY. [L.S.]
